CLAIM

The ornamental design for an ice pack wrap, as shown and described.

DESCRIPTION

FIG. 1 is a front elevational view of an ice pack wrap, in accordance with my new design, the dashed lines indicating stitching;

FIG. 2 is a top plan view of the ice pack wrap of FIG. 1;

FIG. 3 is a right side elevational view of the ice pack wrap of FIG. 1;

FIG. 4 is a left side elevational view of the ice pack wrap of FIG. 1;

FIG. 5 is a rear elevational view of the ice pack wrap of FIG. 1, the dashed lines indicating stitching; and,

FIG. 6 is a bottom plan view of the ice pack wrap of FIG. 1.
